(57) **CLAIM**

We claim the ornamental design for a lapboard, as shown and described.

DESCRIPTION

FIG. 1 is a perspective view of a first configuration of a lapboard, showing my new design;

FIG. 2 is a top plan view of the first configuration thereof;

FIG. 3 is a bottom plan view of the first configuration thereof;

FIG. 4 is a left side elevational view of the first configuration thereof;

FIG. 5 is a right side elevational view of the first configuration thereof;

FIG. 6 is a front elevational view of the first configuration thereof;

FIG. 7 is a rear elevational view of the first configuration thereof;

FIG. 8 is a perspective view of a second configuration of the lapboard;

FIG. 9 is a top plan view of the second configuration thereof;

FIG. 10 is a bottom plan view of the second configuration thereof;

FIG. 11 is a left side elevational view of the second configuration thereof;

FIG. 12 is a right side elevational view of the second configuration thereof;

FIG. 13 is a front elevational view of the second configuration thereof; and,

FIG. 14 is a rear elevational view of the second configuration thereof.

Broken lines are for illustrating unclaimed portions of the lapboard; the broken lines form no part of the claimed design.
